UNITED STATES PATENT OFFICE.

FRED EVANS, OF SUMMIT, NEW JERSEY, ASSIGNOR OF ONE-HALF TO HARTSHORNE & BATTELLE, OF NEW YORK, N. Y., A FIRM COMPOSED OF EDWARD C. HARTSHORNE, SEAVEY BATTELLE, AND FREDERICK W. LUDWIG.

TRACTOR WHEEL.

1,405,823.

Specification of Letters Patent.

Patented Feb. 7, 1922.

Application filed March 27, 1920. Serial No. 369,166.

To all whom it may concern:

Be it known that I, FRED EVANS, residing at Summit, county of Union, and State of New Jersey, have invented certain new and useful Improvements in a Tractor Wheel, of which the following is a specification.

This invention relates to new and useful improvements in tractor wheels, and one of the objects of the invention is to provide a wheel of the above character of simple construction, possessing a maximum of traction and which can be manufactured at a reasonable cost.

A further object of the invention is to provide a wheel of the above character of such construction that it will readily free itself of mud or dirt, which would tend to interfere with the efficient operation of the wheel.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawing, wherein I have illustrated a preferred form of embodiment of my invention:

Figure 1 is an elevational view of my improved wheel.

Figure 2 is a sectional view thereof, taken on line 2—2 of Figure 1; and

Figure 3 is an elevational view of a portion of the face or rim of the wheel.

Referring now to the drawing, wherein similar reference characters refer to similar parts throughout the views thereof, the reference numeral 1 denotes the wheel proper which as will be noted comprises a cylindrically formed box-like structure composed of the two parts 2 and 3 suitably fastened together at their hub portion 4, although it will be understood that auxiliary fastening devices may be employed if desired.

Flanges 5 and 6 formed upon the side pieces 2 and 3 form the rim portion of the wheel. These rim portions 5 and 6 have mounted thereon at spaced intervals pairs of substantially cone-shaped prongs or projections 7 which are adapted to engage with the ground. Extending through the wheel

adjacent the rim thereof are shafts 8, said shafts being equi-distantly disposed about the wheel, as clearly shown in Figure 1, each shaft at its outer end having journalled thereon a roller 9.

Mounted upon the periphery of the wheel is a plurality of feet 10, each foot-piece having a face portion 11, the rear surface of which is in rocking engagement with the rim of the wheel, and also having laterally flanged portions 12 and 13 which lie adjacent lateral faces of the wheel.

It will be noted that the edges of the flanges 12 and 13 of each foot-piece converge in a rearward direction, as shown at 14 and 15. In other words, that they are of wedge-shaped form, the wedge-shaped edges 14 and 15 being engaged respectively with adjacent rollers 9. The construction of the part just described is such that during the rocking movement of the foot-pieces upon the rim of the wheel, due to the engagement of the faces thereof with the ground, the engagement of the wedge-shaped edges 14 and 15 with their respective rollers, limits the extent of the rocking movement of the foot-pieces, whereby the faces thereof are permitted to move into planes at right angles with a vertical line passing through the axis of the wheel.

The foot-pieces 10 are held in the position shown in the drawings by means of springs 16, there being a spring provided at each side of the wheel, and each spring being connected with posts 17 and 18 provided upon each of the side flanges of the foot-pieces. It will be noted that in the present construction each spring is a continuous member extending entirely about the wheel and that said spring operates to hold all of the foot-pieces, save those in engagement with the ground, in the position shown in Figure 1 of the drawings, that is to say, with the face of each foot at right angles to the axis of the wheel.

Provided at the opposite ends of each foot-piece are projections or spurs 19 and 20, which are of course adapted to engage with the ground as is usual in tractor wheels of this character. The face 11 of each foot-piece is provided with a transversely disposed slot 21, each of which receive a pair of the projections or spurs 7, which it will be noted are of substantially the same length

as the projections or spurs 19 and 20. Aside from their function of engaging the ground, the spurs 7 have the further function, in conjunction with the rollers 9, of preventing a 5 circumferential displacement of the various foot-pieces. This function is accomplished by the engagement of the spurs 7 with the lateral walls of the slots 21.

Having thus described this form of embodiment of my invention, the operation thereof should be obvious without further explanation.

It will be observed that during the operation of the wheel the engagement of the 15 foot-pieces with the ground will cause them to assume the position shown in Figure 1 of the drawings, at least two of the foot-pieces being in engagement with the ground at all times. The rocking movement of the 20 foot-pieces upon the rim of the wheel tends to free the wheel of mud, dirt, or other foreign substances, which result is further aided by the engagement of the wedge-shaped edges of the foot-pieces with the rollers 9.

It will accordingly be seen that I have provided a construction well adapted to attain, among others, all the aims and objects above pointed out, in a simple and efficient manner, in that I have provided a wheel 30 specially well adapted for the purposes intended.

As many changes could be made in this construction without departing from the scope of the following claims, it is intended 35 that all matter contained in the above description or shown in the accompanying drawing shall be interpreted as illustrative only and not in a limiting sense.

Having thus described my invention what I claim as new and desire to secure by Let- 40 ters Patent is:

1. A tractor wheel having a rim and a plurality of feet, having portions resting upon the edge of the rim and portions embracing the latter, projections upon said feet, 45 projections upon said rim, which extend through said feet, endless spring members which engage the parts embracing said rim to hold said feet in position upon the latter, and a plurality of rollers mounted upon said 50 rim adapted to engage with said feet and hold them in spaced relation upon said rim.

2. A tractor wheel comprising a pair of cylindrically formed members suitably fastened together, said tractor wheel having a 55 plurality of feet mounted in spaced relation upon its periphery, each of said feet comprising a box-like structure, one part of which lies in rocking engagement with the rim, and the other parts of which embrace 60 the rim, said latter parts having edges which converge toward the axis of the wheel, a plurality of roller members mounted upon said wheel, there being a roller disposed between each of the convergent edges of the 65 parts of said feet which embrace the rim, and spring members common to all of said feet, which hold the latter in movable relation to the rim of the wheel.

In testimony whereof I affix my signature 70 in the presence of two witnesses.

FRED EVANS.
